Warren Plock

UNITED STATES PATENT OFFICE.

JAMES T. DOWDALL, OF GLEN MORRIS, NEW YORK.

SWEATBAND FOR STRAW AND OTHER HATS.

1,420,690.

Specification of Letters Patent. Patented June 27, 1922.

Application filed June 30, 1921. Serial No. 481,506.

To all whom it may concern:

Be it known that I, JAMES T. DOWDALL, a resident of Glen Morris, Queens County, State of New York, and a citizen of the 5 United States of America, have invented certain new and useful Improvements in Sweatbands for Straw and Other Hats, of which the following is a specification.

This invention relates to improvements 10 in sweat bands for hats, particularly straw hats, one of the objects of the invention being to improve the appearance of sweat bands when viewed from the under side of a hat, a further object being to provide a 15 cushioning element at the point where the sweat band contacts with the head, and also to provide a durable wearing surface. To accomplish these results, I combine with the usual leather or fabric sweat-band an insert 20 consisting of a strip of woven straw which extends completely around the sweat band at a point adjacent the point of connection of the brim and crown of the hat with the result that when the hat is placed on a head 25 the insert will contact with the flesh. The woven straw insert will be yieldable and hence will give when the hat is placed upon a head, whereby chafing will be eliminated. The straw insert will provide an efficient 30 bearing surface which will be durable and lasting and will largely prevent the band from breaking down, as it will withstand the action of perspiration better than fabric. Other advantages resulting from my im- 35 provement will hereinafter appear.

I will now proceed to describe my invention in detail, the novel features of which I will point out in the appended claims, reference being had to the accompanying draw- 40 ing, wherein:—

Fig. 1 illustrates a bottom view of a hat provided with my improved sweat band;

Fig. 2 is an enlarged fragmentary sec- 45 tional view; and

Fig. 3 is a fragmentary view illustrating a portion of the sweat band flattened out.

My improved sweat band is made up of a supporting strip 4 of any suitable fabric doubled over at 5 to provide a loop to receive 50 a wire 6 which acts to lend yieldability to the sweat band as a whole, whereby, when the hat is caused to snugly fit a head, the

sweat band will yield owing to the wire member 6. Further elements of the sweat band are a leather strap 7 and a yieldable 55 flexible straw insert 8 which connects the leather band 7 and fabric support 4. The straw insert or strip 8 is secured, along one of its edges, to the leather band by stitching 9 and along its other edge to the support 60 4 by stitching 10. The straw insert 8 forms a substantial continuation of the under surface 11 of the brim 12 of the hat. In practice the insert 8 will form a substantial continuation of the surface 11 of the band 12 65 of the hat. The bight of the fabric support at 5 will also be only slightly perceivable, but the straw insert will predominate. The adjacent edges of the leather band 7 and insert 8 will be abutted, one against the 70 other, and stitched together as at 9. The opposite edge of the insert 8 will be stitched to the fabric support 4, as indicated at 10. The straw insert 8 will yield in all directions; hence, when the hat is placed upon 75 a head, a soft cushioning element will be provided. The straw insert, besides making a tough durable wearing element, will greatly increase the life of the sweat band, as a whole, as it will withstand the action of 80 perspiration, thereby preventing, to a large extent, the breaking down of the sweat-band. The insert 8 will be preferably made out of woven straw and will preferably match the remainder of the hat, indicated by 13, that 85 is to say, so far as appearance is concerned.

The leather band member 7, straw band member 8 and support 4 will be secured together into a unitary structure before being stitched into the hat.

It frequently happens, in straw hats, that the leather bands sag and project below the under surface of the brims. This makes an unsightly appearance, especially should the bands be discolored from use. To obviate 95 this objectionable feature is one of the objects of this invention; hence, I preferably make the insert 8 of woven straw having the same color as the straw out of which the hat is made so as to simulate same.

Having described my invention, what I claim and desire to secure by Letters Patent is:—

1. A sweat band for hats, consisting of a

fabric member, a leather member, and a woven straw member secured together, the straw member connecting the fabric and leather members.

5 2. In a hat, a fabric strip carrying a reed, a sweat band including a leather strip and a strip of straw, the strip of straw incer-

connecting the leather strip and the fabric strip.

3. In a hat, a leather band and a straw band, the two bands forming a sweat band and being connected together edge to edge along one of the longitudinal edges.

JAMES T. DOWDALL.
